ATTORNEY

UNITED STATES PATENT OFFICE.

OSCAR Z. BREWER, OF SPOKANE, WASHINGTON, ASSIGNOR OF ONE-HALF TO HERBERT H. MCNEILL, OF NEW YORK, N. Y.

CARBOY-SHIPPING CONTAINER.

Application filed March 9, 1926. Serial No. 93,461.

This invention relates to carriers or receptacles for liquid containers and more particularly to receptacles or shipping boxes for carboys, though it is noted that the invention is not limited to boxes nor in some respects even to receptacles for carboys.

One object of the invention is to provide a carboy provided with suitable yielding means supporting the carboy at the bottom and sides so as to prevent breakage.

Another object of the invention is to provide a carboy carrier so designed as to reduce to a minimum the material required for making the same.

Another object of the invention is to provide an easily assembled and handled carrier in which the carboy may be quickly and firmly secured.

Other objects of the invention are to improve generally the simplicity and safety of carboy carriers and to provide a receptacle of this kind which is safe, durable and reliable in use and economical to manufacture and into which the carboy may be easily placed and secured and from which it may easily be removed.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved carboy receptacle or carrier which, briefly stated, includes a rectangular box having a spring seat on its bottom on which the carboy rests and provided with corner members comprising corner posts of triangular cross section in respective corners which carry upper and lower blocks across their ends carrying corner springs bridging the blocks at each corner. Upwardly pointed lower wedges and downwardly pointed upper wedges of soft wood seated between the ends of the corner springs respectively and the carboy are provided with corrugations engaging the carboy whereby inequalities of the carboy are impressed in the corrugations to prevent breakage. A top board secured

over the top of the box is provided with an opening receiving the neck of the carboy.

In the accompanying drawing, showing by way of example, one of many possible embodiments of the invention,

Fig. 1 is a vertical sectional view, taken on a vertical plane passing through opposite corners of the box;

Fig. 2 is a horizontal sectional view, partly in plan, taken on the line 2-2 of Fig. 1;

Fig. 3 is a front or side elevation of the box;

Fig. 4 is a plan; and

Fig. 5 is a perspective view showing an assembled corner member.

My improved container or carrier for carboys or other liquid containers comprises a frame or box 5 having bottom and side walls 6 and 7 and strips 8 forming shoes under the edges of the bottom of the box and horizontal strips 9 forming handles secured across the mid part of the outer face of opposite side walls 7 of the box, though the invention is in no way limited to the construction or details of the box.

A bottom disk 10 is secured concentrically on the inner face of the bottom wall 6, and a plurality of superposed horizontal boards 11 are placed on said disk, each layer being disposed so that the grain runs at right angles to the grain in the adjacent layers as indicated at 12, Fig. 2, to cooperate to form a bottom spring or cushion seat for the carboy 15.

Corner posts 16 of triangular cross section (Fig. 5) fitting in the respective vertical corners of the box and extending substantially from top to bottom thereof with their exposed faces 17 at 45 degrees to the side walls, carry upper and lower corner blocks 18 and 19 secured across the ends respectively of said exposed faces 16 and in turn carry corner springs 20, one at each corner of the box, mounted on and bridging the corner blocks thereof, each corner spring being provided with a lateral bead 21 along each side of its main exposed face.

Upwardly pointed lower wedges 22 fitted between said beads 21 at the lower end of each corner spring with their butts against the bottom wall are provided with longitudinally corrugated exposed faces 23 against

which the carboy may be wedged; while downwardly pointed upper wedges 25 seated or nailed between the beads of the upper end of the corner springs respectively and wedged between the carboy and the corner spring are provided with longitudinally corrugated exposed faces 26 engaged with the carboy. Said wedges are made of soft wood, whereby the inequalities of the carboy are impressed into corrugations 23 and 26 to avoid breakage and to hold the carboy firmly.

A top board 28, made in sections if desired, is secured over the top of the box 15 against the upper corner blocks 18, the ends of the posts 16 and the butts of the upper wedges 25, and is provided with a large opening 29 receiving the neck and shoulder of the carboy, said opening being formed by 20 removing from the top board the material which may be used for the disk 10.

The various parts of the carrier may be made of any suitable lumber or material, though the boards 11 and wedges 22 and 25 25 are preferably made of soft wood.

To pack the carboy the corner elements shown in Fig. 5, exclusive of the corner posts, may be assembled and nailed together, except that the top wedges 25 are left out until 30 the above mentioned elements first, and then the carboy, are lowered into the box, after which these wedges are forced into place and nailed. The top boards are then nailed on, thus holding the corner members in place; 35 or the upper and lower spacing blocks 18 and 19 may be nailed to the upper and lower ends of the corner posts, and the vertical spring pieces and lower wedges nailed in place after which the carboy may be lowered 40 and the upper wedges inserted and nailed.

When the carboy is packed as noted above the carboy may be removed by pulling out upper wedges and withdrawing the carboy. If the first noted above method is used in 45 packing, the corner spring assemblies may be lifted out for inspection. This construction permits repairs to be made on the frame of the box without injuring spring assemblies, and old spring assemblies may be replaced with new ones without injury to the 50 frame of the box.

I claim as my invention:

1. In a carrier for carboys, in combination, a rectangular box, corner posts triangular in 55 cross-section disposed in the corner angles of said box and extending from the top to the bottom of the box, spring members secured at their ends to the flat inward faces of the corner posts and extending longitudinally 60 thereof for the length of the corner posts and spaced away from said faces for the portions of their lengths between said ends and having guideways on their inward faces, and a pair of triangular wedges for each spring 65 member engaging the guideway of the spring

member and spaced away from each other in apex to apex relation, one of said wedges being at the top of the spring member and the other being at the bottom of the spring member.

2. In a carrier for carboys, in combination, a rectangular box having a cover removably secured thereto, corner posts triangular in cross-section disposed in the corner angles of said box and extending from the top to the bottom of the box, spring members secured at their ends to the flat inward faces of the corner posts and extending longitudinally thereof for the length of the corner posts and spaced away from said faces for the portions of their lengths between said ends and having guideways on their inward faces, and a pair of triangular wedges for each spring member engaging the guideway of the spring member and spaced away from each other in apex to apex relation, one of said wedges being at the upper end of the spring member and the other being at the lower end of the spring member, said upper wedges engaging on one of their sides the upper side of the carboy and said lower wedges engaging on one of their sides the lower side of the carboy, said upper wedges being retained in wedging position by said cover when the cover is secured in covering position, the carboy being releasable from the carrier by removal of said cover and moving said upper wedges upwardly in said guideways.

3. In a carboy carrier of the character described, in combination, a corner post triangular in cross-section, a spring member having on one face a longitudinally extending guideway, and a pair of substantially right angle triangle wedges engaging on one of their sides said guideway and spaced apart in apex to apex relation, one of said wedges being at the upper end of said spring member and the other at the lower end of the spring member, said spring member on its face opposite said guideway being secured at its ends to the flat inward face of the corner post and extending longitudinally thereof and spaced away therefrom for the portion of the spring member between said ends, the respective hypotenuses of the wedges engaging the upper and lower side portions of the carboy for retaining the carboy in the carrier, the pressure of the carboy on the wedges tending to bend the mid portion of the spring member outwardly towards the corner post whereby the carboy is yieldably maintained in the carrier.

4. A carrier for carboys comprising a box; upright members disposed against the walls of the box; an upwardly pointed lower wedge member disposed against the lower end of each upright member and provided with an exposed face against which the carboy may be wedged; and downwardly pointed upper wedge members separate from the

lower wedge members and disposed against the upper end of the upright members respectively and wedged between the carboy and the upright member; one of said members at each plane of contact with another of said members being provided with spaced beads between which the other member seats.

5. A carrier for carboys comprising a box having bottom and side walls; upright members disposed against the side walls; and an upwardly pointed lower wedge member disposed against the lower end of each upright member with its butt against the bottom wall, and provided with an exposed face against which the carboy may be wedged; means preventing lateral movement between contacting members including longitudinal spaced beads carried on one of the members and between which the other member is seated; and downwardly pointed upper wedges on the upper end of the uprights respectively and wedged between the carboy and the upright member.

6. A carrier for carboys comprising a box; uprights disposed against the side walls of the box each provided with a lateral bead along the side of its main exposed face; an upwardly pointed lower wedge fitted between said beads at the lower end of each upright provided with an exposed face against which the carboy may be wedged; downwardly pointed upper wedges seated between the beads of the upper end of the uprights respectively and wedged between the carboy and the upright; and a top board secured over the top of the box against the butts of the upper wedges.

7. A carrier for carboys, comprising a box; uprights disposed against the side walls

of the box; and downwardly pointing upper wedges and upwardly pointed lower wedges between the ends of the uprights and the carboy for holding the carboy against either upward or downward movement; and boards secured on the top and bottom of the box against the butts of the upper and lower wedges.

8. A carrier for carboys, comprising a box; uprights disposed against the walls of the box; and downwardly pointing upper wedges and upwardly pointed lower wedges fast on the uprights between the ends of the uprights and the carboy positively holding the carboy against either upward or downward movement.

9. A carrier for carboys, comprising a frame; posts disposed around the frame; a block across the end of each post; an intermediately yieldable spring bridging the blocks of each post; and separated upwardly pointing upper wedges and upwardly pointed lower wedges between the ends of the springs and the carboy engaging the carboy at active portions of the wedge remote from said blocks, whereby said portions yield with the springs.

10. A carrier for carboys comprising a box; uprights disposed against the walls of the box each provided with a lateral bead along the side of its main exposed face; and inwardly pointed wedges fitted between said beads on each upright and provided with an exposed face against which the carboy may be wedged.

Signed at Spokane in the county of Spokane, and State of Washington, this 10th day of February, A. D. 1926.

OSCAR Z. BREWER.
